EGG CANDLING DEVICE

George H. Siegal, Pittsburgh, Pa.

Application July 7, 1933, Serial No. 679,361

3 Claims. (Cl. 99—8)

This invention relates to improvements in egg-candling devices.

The object of my invention is to provide an egg-candling device which is mounted on the wall and which can be easily raised, lowered or swung side-ways if so desired.

Another feature of my invention is to provide an egg-candling device, which is adapted to be mounted in such a manner where it will be 10 out of the way when candling eggs or when replacing crates on the work-bench, yet at the same time the device is supported in a position where it may be conveniently reached depending on the height of the work-bench and the desire 15 of the person manipulating the same.

Another distinctive feature of my invention is to provide an egg-candling device which automatically permits light-rays to issue through the bottom of the box when in raised position, there- 20 by illuminating the egg-crate which is placed beneath the device.

Yet another object of my invention is to provide an egg-candling device in which the electric light socket is easily inserted or removed 25 and in which said light socket is held rigidly in place between the two cover-halves of the box cover.

Still another object of my invention is to provide an egg-candling device of simple, economical 30 construction, which will occupy but little space on the wall and can be produced for comparatively small expense.

My invention further comprises the novel details of construction and arrangements of parts, 35 which in their preferred embodiments only are illustrated in the accompanying drawing which forms a part of this specification, and in which:

Figure 1 is a side elevation of my egg-candling 40 device, showing the manner of mounting the same on a wall and also showing in full lines the device in lowered position, ready for candling eggs and in dot and dash lines the device in raised position, ready to throw light-rays 45 through the bottom opening of the box-part of the device on a crate of eggs.

Figure 2 is a front view of Figure 1.

Figure 3 is a top elevation of the wall-bracket 50 part of the device along line 3—3 in Figure 1, showing in dot and dash lines two additional positions of the swinging arms with parts of the latter broken away.

Figure 4 is a cross-sectional view along line 4—4 in Figure 5.

Figure 5 is a bottom elevation of the box-part

of the device showing the lid in closed position.

Figure 6 is a top elevation of the box-part of the device showing in dot and dash lines the sliding covers ready to receive therebetween an electric light socket.

Figure 7 is a detail view of the guide-bar which holds the retaining bar between one of the swinging arms and the guide-bar.

Figure 8 is a rear elevation of the lower part of the box showing the slot for permitting the lid-operating bar to enter the box.

Figure 9 is an isometric view of the sliding cover atop the box, ready to receive an electric light socket.

In the embodiment of my invention illustrated 70 I show merely in formal manner a box 10, pivotally attached to swinging arms 11. These arms 11 are also pivotally connected to a wall-bracket 12.

The box 10 comprises a rectangular receptacle consisting of a front-wall 13, side-walls 14 and 15 and the rear-wall 16. Side-walls 14 and 15 and the front-wall 13 are made preferably from one piece of sheet metal and spot welded to the rear wall 16 in a manner as shown in 80 Figure 5. The lowermost ends of said walls are mitered and bent over inwardly to form a frame 17 and an opening 18.

As shown in Figures 1, 2, 6 and 9, the top of the box 10 is provided with a sliding cover 19 which is made in two halves, each half being provided at its abutment with a centrally disposed semi-circular opening 20, so as to produce a round aperture 21 when the sliding cover is in closed position.

Both halves of said sliding cover 19 are slidably mounted on outwardly bent flanges 22 formed integrally with the side-walls 14 and 15 of box 10 (Figure 9). Small stop-pieces 23, spot-welded to the inner side of said cover 19, are provided for to prevent the latter from sliding out of engagement of the flanges 22 of the box 10 when inserting an electric light socket 24.

The mounting of said electric light socket 24 is extremely simple and is as follows:

The cover-halves of cover 19 are manually moved apart by means of the bent-down portions of the cover or finger-holds 26 provided at the end of each cover-half of said cover 19, when so moved apart, the cover assumes a position as shown in Figure 9. After the lamp-socket 24 is inserted between the two cover-halves of cover 19, said cover-halves are then slipped together as shown in Figure 6.

The edge of the now circular aperture 21 of cover 19 grips the socket 24, thereby holding the latter firmly in that position, ready for use.

5 The box 10 is mounted for up, down or side movement on a wall-plate 25 by means of two substantially parallel swinging arms 26 and 27 which are pivotally connected to said wall-plate 25 on a vertically disposed swinging-bar 28 which is provided at its upper and lower ends with pivot-pin extensions 29 and supported by angle-pieces 30 spot welded to said plate 25. These angle-pieces are provided with suitable apertures 31 for the reception of said pivot-pin extensions 29.

15 To retain the device in a position as shown in Figures 1 and 2, or as shown in dot and dash lines in Figure 3, I provide a horizontally disposed flat-spring 32, both ends of which are spot welded to the wall-plate 25 and located about midways of the same.

20 Co-operating with said flat spring 32 are a pair of angular shaped retaining members 33 and 34, welded to swinging-bar 28 in a manner as best shown in Figures 1, 2 and 3. The horizontal arms of said retaining members 33 and 34 are rounded as at 35 and 36. These rounded portions produce a cam action in co-operation with spring 32 and exert a pressure against said flat-spring 32 when the device is in a position as shown in Figures 1, 2 and 3.

25 Due to the open space 37 obtained between said retaining members 33 and 34 when assembling, the device will retain that position until manually moved side-ways, which operation will slightly compress the flat-spring 32 and again relax the latter when the device is swung ninety degrees to a position as indicated in dot and dash lines in Figure 3. When the device is in that position no pressure is exerted against the flat-spring 32, until the device is again brought to a position as shown in full lines in Figure 3.

30 The rear wall 16 of the box 10 is provided with a vertically disposed and angular shaped support 38 on which is pivotally mounted a pair of parallelly disposed swinging arms 26 and 27. The other end of these swinging arms is pivotally connected to the swinging bar 28, as previously described. Both of said swinging arms 26 and 50 27 are pivotally united by a connecting link 39, the lower end of which is pivotally connected to the lid-operating lever 40.

35 This lid-operating lever is mounted in parallel alignment with the swinging arms 26 and 27 and is pivoted by a pin connection 41 near the bottom of support 38. The lowermost terminal of said lever 40 is twisted, as indicated by the numeral 42 and strengthened by a short twisted strip 43 disposed in opposite direction of twist 42 and spot welded to lever 40, as shown in Figure 5.

40 The twisted ends 42 and 43 are spot welded to the lid 44 which closes the opening 18 of box 10 when the device is in a position as shown in full lines in Figures 1 and 2.

45 Access is had to the interior of the box 10 for the purpose of inserting the end of lever 40 by means of a vertical slot 45 (Figure 8) located in the rear wall 16 of said box 10.

50 70 A bar 46 provided with notches 47 and a handle extension 48 is pivotally mounted on the upper swinging arm 26 about midway between the connecting link 39 and the vertically disposed support 38. Bar 46 is held from moving sideways by means of a guide-bar 49, one end

of which is spot welded to the lower swinging arm 27 and the other end of which is held apart sufficiently to permit free movement of said bar 46 by a shouldered pin 50 (Figures 1 and 7). This pin 50 also serves as a lock to hold the device in a downward position by means of the notches 47 in bar 46 and the coil spring 51.

80 To retain the device in an "up" position as shown in Figure 1 in dot and dash lines, a coil-spring 52 properly anchored at 53 and 54 is used. Springs 51 and 52 are in an expanded condition when the device is "down" and in a contracted condition when the device is "up".

85 The operation of my device is as follows:

90 Assuming that the device is secured to a wall in a dark-room and is in a "down" position as shown in full lines in Figure 1 and a crate of eggs is placed beneath the box 10 as shown and it is further assumed that the lamp 55 in box 10 is energized. The operator faces the front 95 of box 10 which is provided with a test-hole 56. When the device is in "down" position the bottom opening 18 is closed by the lever-operated lid 44, thus preventing light rays from lamp 55 issuing from the box 10, with the exception 100 through the rounded test-hole 56.

105 The operator takes the eggs from the crate 57 and applies the same against the test-hole 56, so as to permit the utilization of the rays issuing through said hole 56 to inspect the condition of the egg. The eggs are then placed into another empty crate.

110 Since the device is produced preferably from sheet metal it may be found advisable to fasten a felt or leather padding around the test-hole 56 to prevent injury to the eggs. This would also allow the operator to place the eggs rapidly against the padding without exercising that extraordinary degree of caution which would considerably reduce the number of eggs to be 115 candled at a given time.

115 To provide ample illumination, for instance, when it is necessary to replace crates etc. or in order to provide sufficient space around the work-bench when the device is not in use, the 120 egg-candler may be placed in an "up" position. The operator grasps the free end of bar 46 and forces the same rearwardly, thereby expanding spring 51 and at the same time releasing pin 50 from notch 47 and also releasing hand hold of 125 the free end of bar 46.

130 This operation will bring the device in an "up" position as shown in dot and dash lines in Figure 1 of the drawing; it also will expose the opening 18 at the bottom of box 10, thus permitting the rays of light from lamp 55 to issue ample illumination to places where needed.

135 As designed the device furnishes light only where desired and the mounting of the device prevents it from being upset.

The device may be applied in any desired way depending on the height of the work bench and the desire of the person using the same.

140 Though I have described with great particularity the details of the embodiment of the invention herein shown, it is not to be construed that I am limited thereto, as changes in the arrangement of parts and substitution of equivalents may be made by those skilled in the art without departing from the invention as defined in the appended claims.

145 I claim:

1. In a device of the character described, comprising a box, supported from a wall-plate having a vertically disposed swinging-plate, a pair 150

- of parallelly disposed swinging-arms mounted for up, down or side movement pivotally connected to said box and swinging arms, said box adapted to support a lamp projecting into the
5 same and provided at the front-wall with a test-hole, cam operated means for retaining the device in a forward or lateral position and spring means for retaining the device in an up or down position, said cam means comprising a horizontally disposed elongated flat spring adapted to be securely fastened at both ends to said wall-plate and adapted to be in cooperation with a pair of oppositely directed, horizontally disposed and cam-shaped angle-pieces securely mounted
10 to said swinging plate.
2. In a device of the character described, comprising a box supported from a wall-plate and having a vertically disposed swinging-plate, a pair of parallelly disposed swinging-arms
15 mounted for up, down and side-movement, pivotally connected to said box and to said swinging-arms; said box provided at the front with a test-hole and provided at the top with a sliding cover and at the bottom with an internally disposed bottom cover, said top cover adapted to support a lamp projecting into said box, means for automatically opening said bottom cover when the device is in an "up" position and means for automatically closing said bottom cover when the device is in a "down" position.
